Primary Examiner — T. Chase Nelson*Assistant Examiner* — Mark Cavanna(74) *Attorney, Agent, or Firm* — Kelly Kordzik; Matheson Keys Daffer & Kordzik PLLC**(57) CLAIM**

The ornamental design for a heart-shaped article, as shown and described.

DESCRIPTION

FIG. 1 is a front perspective view of a heart-shaped article showing my new design with an open wound;
 FIG. 2 is an enlarged top plan view thereof;
 FIG. 3 is an enlarged bottom plan view thereof;
 FIG. 4 is an enlarged right side elevational view thereof;
 FIG. 5 is an enlarged left side elevational view thereof;
 FIG. 6 is a front elevational view thereof; and,
 FIG. 7 is a back elevational view showing a mended wound. The broken lines in FIGS. 1-6 are included for the purpose of illustrating unclaimed portions of the heart-shaped article and form no part of the claimed design.

1 Claim, 7 Drawing Sheets---
